United States Patent Office

Des. 178,808
Patented Sept. 18, 1956

178,808

BOTTLE

Theodore Rosenak, Milwaukee, Wis., assignor to Blatz
Brewing Company, Milwaukee, Wis., a corporation of Wisconsin

Application March 11, 1954, Serial No. 29,463

Term of patent 14 years

(Cl. D58—8)

The figure is an elevational view of a bottle showing my new design.

The portions of the bottle not shown are the same as those shown in the drawing.

I claim:

The ornamental design for a bottle, as shown and described.
